UNITED STATES PATENT OFFICE

169,072

HAIRPIN TRAY

Elizabeth K. Kupinske and Anne K. Wargo,
Fairfield, Conn.

Application November 13, 1952, Serial No. 22,269

Term of patent 7 years

(Cl. D86—10)

To all whom it may concern:

Be it known that we, Elizabeth K. Kupinske and Anne K. Wargo, each a citizen of the United States and each a resident of the town of Fairfield, county of Fairfield, and State of Connecticut, have invented a new, original, and ornamental Design for a Hairpin Tray, of which the following is a specification, reference being had to the accompanying drawing, forming part thereof.

Fig. 1 is a top view of a hairpin tray, showing our new design.

Fig. 2 is a front view thereof.

Fig. 3 is a side view thereof.

Fig. 4 is a bottom view thereof.

We claim:

The ornamental design for a hairpin tray, as shown.

ELIZABETH K. KUPINSKE.
ANNE K. WARGO.
